L. E. HARRIS

BUFFER BLOCK

Filed April 15, 1921

UNITED STATES PATENT OFFICE.

LUTHER E. HARRIS, OF PHILADELPHIA, PENNSYLVANIA, ASSIGNOR TO HARRIS & WOLFREY, A PARTNERSHIP CONSISTING OF LUTHER E. HARRIS AND JOHN N. WOLFREY.

BUFFER BLOCK.

Application filed April 15, 1921. Serial No. 461,665.

To all whom it may concern:

Be it known that I, LUTHER E. HARRIS, a citizen of the United States of America, and resident of Philadelphia, in the county of Philadelphia and State of Pennsylvania, have invented certain new and useful Improvements in Buffer Blocks, of which the following is a specification.

This invention relates to sand papering blocks or holders, and has for its object the provision of novel means for the economical use of sand paper whereby the sand paper may be manipulated more expeditiously and effectively, and whereby it may be held in a manner in order that the whole surface of the sand paper will be effectively employed, a condition which will avoid waste of the material.

A still further object of this invention is to provide a sand paper holder employing clips to engage the sand paper, associated with novel means for holding the clips in place to clamp the sand paper, whereby the said clips may be readily applied to or removed from the holder, for the purpose of clamping the sand paper or releasing it when changes are to be made.

A still further object of this invention is to produce a sand papering block having a yieldable surface, associated with a recessed portion of the face of the block, in order that the yieldable surface may give sufficiently to permit the sand paper to conform slightly to the contours of headings or edges of materials being treated.

It is a further object of this invention to provide a sand papering block or holder of the character indicated which will afford a firm hand grasp for its manipulation, and which will prove comparatively inexpensive in manufacture.

With the foregoing and other objects in view, the invention consists in the details of construction, and in the arrangement and combination of parts to be hereinafter more fully set forth and claimed.

In describing the invention in detail, reference will be had to the accompanying drawings forming part of this application where-in like characters denote corresponding parts in the several views, and in which—

Figure 1 illustrates a perspective view of a

sand paper holder embodying the invention;

Figure 2 illustrates a sectional view on the line 2—2 of Fig. 1;

Figure 3 illustrates a sectional view on a line corresponding with the line 3—3 of Fig. 2;

Figure 4 illustrates a perspective view of the sand paper clamp; and

Figure 5 illustrates a perspective view of the plate clamp.

In these drawings 5 denotes the base of the block, the surface of which has a facing 6, preferably of leather, which is secured thereto by any suitable adhesive. The bottom surface of the base is longitudinally grooved as at 7, and this groove is preferably in the transverse center of the base, although the inventor does not wish to be limited with respect to its exact location. The facing 6 is slit longitudinally as at 8, along the axis of the recess and this forms lips or flaps which may be pressed into the groove. The groove is of such depth as to permit the facing to yield to a degree which will allow the sand paper to conform to the contours of edges of materials being finished or to the contour of beads or flanges, a condition which renders it possible to treat a greater surface than it is possible to treat when the sand paper is flat. Near each end of the base there are posts or lugs 9 designed to connect the handle 10 to the base, and preferably, the distance between the handle and base is such as to accommodate the thumb and fingers of an operator in order that he may have a firm grasp on the handle.

Preferably the handle has recesses or seats 11 near its ends, and the recessed portions of the handle have screws 12 to engage the clamping nut 13. Slots or channels 14 extend longitudinally of the handle at its ends and merge with the recesses or seats, and these slots or channels form clearances for the reception of the plates 15, which plates terminate in clamping jaws or clips 16 which are intended to bear against the ends 17 of a sheet of sand paper 18 which is applied to the lower surface of the base, it being understood that the ends of the sand paper embrace the ends of the base and extend thereover and into engagement with the posts or lugs 9, against which they

are held by the clamping jaws. The plates 15 have longitudinally extending slots 19 forming clearances for the nuts, and the said clamping nuts have flanges 20 which bear 5 against the upper surfaces of the plates with such friction as to retain them against movement, yet affording a means by which the plates may be released by backing the nuts. The flanges are relatively wide to present 10 contacting surfaces which exert friction on the plates to effectively hold them when the nuts have been adjusted to cause the flanges to bear against the said plates.

It has been found in practice that a properly proportioned base will be of such length 15 as to receive sand paper of the conventional sizes and permit the sand paper to embrace the ends of the base and extend slightly thereabove, in order that the surfaces of the 20 sand paper at the ends may be engaged by the clamps, as stated.

The screws 12 are shown as extending vertically through the base and through the

posts or lugs 9 and terminating in the recesses 11.

25

I claim:

1. In a buffer block, a body and a handle, the said handle having slots extending inwardly from the ends and recesses in the top with which the slots merge, threaded studs 30 projecting into the recesses, clamping elements having slotted portions extending through the slots of the handle into the recesses, members threaded on the studs and bearing on the slotted portions of the clamps for 35 frictionally retaining the clamps in place, the said clamps having jaws overlying portions of the ends of the body and adapted to clamp sand paper against the said ends.

2. In a buffer block, a base having a yieldable facing thereon slit longitudinally, the said base having a channel under the slit portion of the facing, and means for securing sand paper to the base.

LUTHER E. HARRIS.
